(57) **CLAIM**

The ornamental design for a coaxial connector, as shown and described.

DESCRIPTION

FIG. 1 is a perspective view of the preferred coaxial connector design, showing end caps disposed in axial alignment on each end of the connector.

FIG. 2 is an end elevational view of the preferred coaxial connector design, showing an end on the right side of FIG. 1.

FIG. 3 is a side elevational view of the preferred coaxial connector design.

FIG. 4 is an end elevational view of the preferred coaxial connector design, showing an end on the left side of FIG. 1.

FIG. 5 is a plan view of the preferred coaxial connector design.

FIG. 6 is an end elevational view of the alternative embodiment of the coaxial connector design, showing a second end; and,

FIG. 7 is a plan view of the alternative embodiment of the coaxial connector design.

The broken lines are for illustrative purposes only and form no part of the claimed design.
